United States Patent Office

Des. 187,646
Patented Apr. 12, 1960

187,646

COMPUTER

Walter F. Kraus, Poughkeepsie, N.Y., assignor to International Business Machines Corporation, New York, N.Y., a corporation of New York

Application September 22, 1959, Serial No. 57,644

Term of patent 14 years

(Cl. D26—5)

FIG. 1

Fig. 1 is a perspective view of a computer embodying my new design; and

Fig. 2 is a perspective rear view thereof.

The essential features of my design reside in the portions shown in solid lines in the drawings.

I claim:

The ornamental design for a computer, as shown and described.
